(57) **CLAIM**

The ornamental design for a dominoes tile set with curved pieces, as shown and described.

DESCRIPTION

FIG. 1 is an upper right front perspective view of a game piece;

FIG. 2 is a top plan view of a game piece;

FIG. 3 is a front elevational view of a game piece;

FIG. 4 is a right side elevational view of a game piece;

FIG. 5 is a left side elevational view of a game piece;

FIG. 6 is a rear elevational view of a game piece;

FIG. 7 is a bottom plan view of a game piece; and,

FIG. 8 is a top plan view of a set of game pieces. All game pieces are identical to the game piece illustrated in FIGS. 1-7 except for the number pattern which is located on the top of each game piece.
